UNITED STATES PATENT OFFICE.

WILLIAM G. WOOD AND WILLIAM A. MEYER, OF SACRAMENTO, CALIFORNIA, ASSIGNEES,
BY DIRECT AND MESNE ASSIGNMENTS, TO BERKELEY LIGHT CORPORATION, A COR-
PORATION OF NEVADA.

HEADLIGHT.

1,330,419.

Specification of Letters Patent. Patented Feb. 10, 1920.

Application filed April 5, 1916. Serial No. 89,115.

To all whom it may concern:

Be it known that we, WILLIAM G. WOOD and WILLIAM A. MEYER, citizens of the United States, residing at Sacramento, in the county of Sacramento and State of California, have invented new and useful Improvements in Headlights, of which the following is a specification.

The present invention relates to improvements in head-lights for vehicles, such as automobiles, street cars, railway cars and the like.

Much danger and discomfort are occasioned by the fact that the head-lights of automobiles, street cars and the like, being now usually reflected by a parabolic reflector, produce by their glare a blinding effect upon persons walking or riding in front of the vehicle into whose eyes they are directly reflected. It has been attempted to remedy this evil by the use of what are called "dimmers," the object of which is to partially obscure the upper portion of the head-light. But, besides the fact that these dimmers involve a sheer waste of illumination, they do not even have the effect intended. The result of dimming the upper portion of the head-light is only to reduce the amount of light by nearly one-half, and not to confine the light to a short distance above the ground. The use of the dimmers merely renders the light less powerful than before, with the obvious disadvantage that the road surface is no longer sufficiently illuminated.

One object of the present invention is to provide a head-light, which, while throwing a very strong light upon the surface of the road in front of the vehicle to a very considerable distance, will not shine into the eyes of a person walking or riding in front of the vehicle.

A further object of the invention is to provide simple and effective means whereby the direction of the beam of light from the head-light can be varied both horizontally and vertically, without adjusting the frame of the head-light itself.

In the accompanying drawings, Figure 1 is a vertical section of our improved head-light; Fig. 2 is a front view thereof; Fig. 3 is a section on the line 3-3 of Fig. 1; Fig. 4 is a view, similar to Fig. 1, of a modified form of the invention.

Referring to the drawing, 1 indicates a casing of a head-light, to the sides of which

are secured the usual lugs 2 having vertical apertures 3 in which can be received the upper ends of standards to which the lugs are secured by means of set screws. The interior of said casing is of a dead black color.

In the rear of the narrow lower portion of said head-light is secured an ordinary plug connection 4 for lamp cords 6, which are connected to an Ediswan socket 7 of a small lamp 8. Said socket 7 is pivoted at the bottom, as shown at 9, to extensions 11 from an internally threaded tube 12 having a shoulder 13 into which tube 12 is screwed a screw 14 extending through a hole in the casing 1 and having a shoulder 15 bearing against the outer surface of the casing 1, between which casing and the shoulder 13 is a compressed coiled spring 16, tending always to move the lamp socket 7 from the casing. By screwing the screw inward in the threaded tube 12, the lamp can be drawn downwardly, or toward the part of the casing through which the screw extends, and by screwing the screw outwardly the spring 16 is permitted to move the lamp from said part of the casing.

In the front upper portion of the casing is a hole closed by a glass window 17 of cylindrical curvature, secured in the usual manner to the casing 1. Near the bottom of said hole there is hinged to the casing, as shown at 18, a parabolic reflector 19 having a plane margin 21. At the apex of said reflector is a hole around which extends outwardly a tube 22 fitting over the cylindrical socket 7 and having diametrically opposite open-ended slots 23 to receive the ends of a pin 24 extending through the Ediswan socket to prevent the latter turning with the screw 14. The outer side of the margin 21, opposite to its hinge 18, has a hole 27 therethrough through which can extend a threaded stud 29, supported upon an extension 31 from a band 32 soldered around the inside of the casing, and on which band rests the margin of the reflector, a nut 33 being screwed on said stud 29. The lamp 8 is secured by bayonet slots 34 in the cylindrical socket 7 and at the focus of the parabolic reflector, which is so arranged that the light from the lamp is reflected upwardly and rearwardly, and so that a beam of light, of substantially the same width as that of the parabolic reflector, is thrown against a plane, approximately elliptical mirror 36.

When the window is swung outwardly on

its hinge, the parabolic reflector can, the screw 14 having been removed, be swung outwardly on its hinge 18 for inspection and repair, the lamp cords being of sufficient length to permit this outward movement.

On the margin of the mirror, adjacent to the ends of its major axis, are secured sockets 37 pivoted to the ends of arms 39 depending from the cross member of a T piece 41 pivoted by means of a stem 42 in a hole 43 in a frame 44 having three legs secured to the casing, a central leg 46 and two side legs 47. The central member 48 of said T piece extends rearwardly and has therein a longitudinally extending open-ended slot 51 above, but spaced from, the central leg 46 of the frame. Between said central member and central leg is a guide piece 52, which has a contracted portion 53 depending through a slot 54 in the central leg 46, said contracted portion being threaded below said leg 46 and having thereon a nut 56. Through said guide piece, and between said central member and central leg, extends a push bar 58, an inner portion of which is mortised on each side, as shown at 59, and fits within the guide piece 52. A screw 61 extends downwardly through the open-ended slot 51 in the central member 30 of the T piece and is screwed into said mortised portion of the bar. The bar 58 extends through a hole 62 in one side of the casing, and is formed on the outside of the casing with a hole 63 by which it can be connected with means for moving the bar in or out. It is preferred to use means by which this bar can be moved in or out in conformity with the movement of the steering mechanism by which the vehicle is turned to one side or the other. We do not illustrate and describe such mechanism, because many mechanisms of like character, which have been used for turning the head-light as a whole with the movement of the steering mechanism, can be readily adapted for turning the reflector here shown.

It is evident from the above construction that, if the push bar be moved in or out, the central member of the T piece will be moved from one side to the other and the mirror will be correspondingly turned about a vertical axis.

To turn the mirror about a horizontal axis the upper part of the stem 42 is threaded and screws through a nut 60 having an extension pivoted, as shown at 64, to a yoke 66, the arms of which are pivoted, as shown at 67, to brackets 68 secured upon the back of a mirror and extending horizontally thereon. When said threaded stem is turned it is evident that the mirror is moved up or down about a horizontal axis. On the outside of the casing and on the square end of a reduced upper portion of the stem 42 extending through the casing is

secured a handle 71, by which the stem can be turned. To the central lower portion of the back of the mirror is secured by solder 72 a hook 73 to which is secured one end of a stretched coiled spring 74, the other end of which is secured to the rivet 76 which secures the central leg 46 to the casing.

In Fig. 4 is shown a modification of the means for turning the mirror about a horizontal axis. Instead of the threaded stem 42, there is now used a smooth stem 77, around which is a sleeve 78, which, like the nut 60 is attached to the yoke 66, and said sleeve 78 is formed with semi-circular teeth 79 forming a rack, and engaged by a segment gear 81, pivoted at 82 on a bracket 83, and having a slot 84, which is engaged by a pin 86 carried upon the top of a rod 87, having bearings 88, 89 in the central lug 46 and casing 1 respectively. The lower end of said rod 87 is formed with a rack 91 engaged by a pinion 92 on a suitably mounted shaft 93 operatively connected with means, located at the driver's seat, for turning the same.

This construction of lamp contains important practical advantages. Heretofore head-lights for automobiles with parabolic reflectors have not been found satisfactory on account of the blinding glare which they produce upon an observer in front. To avoid this blinding glare all of the rays reflected from the parabolic reflector, except those proceeding from the focus of the parabola, should be absorbed or got rid of, if possible, for they diverge to such an extent that it is not practicable to prevent them from striking the eye of an observer at a dangerously short distance in front of the car. Only those rays should be allowed to illuminate the roadway which come from points so close to the focus of the parabola that their divergence is so small that it is possible to keep them below the eye of an observer at a safe distance in front. Now our construction enables this to be accomplished, for, in the first place, the source of light, as an electric lamp, can be arranged so that the focus of the parabola is at the extreme front end of said source, and therefore no rays of light proceed from points in front of the focus of the parabola. And the rays of light proceeding from points too far behind the focus of the parabola, and which, after reflection at the parabolic mirror, would diverge too much, and strike the eye of an observer at less than a safe distance, are reflected by the parabolic mirror in such paths as to escape the plane mirror altogether, or, when reflected thereby, are reflected to the dull black interior of the lamp, and are lost.

Although only a minute portion of the whole of the source of light is utilized, namely, that at the extreme end of said

source, yet this portion is utilized so effectively by the parabolic reflector that the light is quite sufficient to illuminate the roadway.

5. The utility of our invention therefore resides in the fact that, first, by the use of a plane mirror, we reflect again the rays of light proceeding from a parabolic reflector, and thus are enabled to select only those 10 rays which ultimately diverge so slightly as not to strike the eye of an observer within a safe distance, and, secondly, we are enabled to adjust the position of the source of light so that the extreme front end of 15 said source is at the focus of the parabolic reflector, thus rendering it easier to shut out all the rays which would blind the observer.

We claim:—

1. A vehicle lamp of the character described, comprising a casing having a translucent portion, a parabolic reflector arranged in said casing, a source of light axially adjustable in said reflector; a plane reflector, and non-reflecting surfaces arranged about 25 said plane reflector and the translucent portion.

2. In a vehicle lamp, the combination of a casing entirely inclosed except for a window opening at the front, the interior of 30 the casing having a non-light-reflecting surface, a parabolic reflector in the casing disposed below the window opening, a source of light adjustably mounted in the focus of the reflector and a mirror in the casing above 35 the parabolic reflector receiving the rays of light from the parabolic reflector and reflecting them through the window.

3. In a vehicle lamp, the combination of a casing entirely inclosed except for a window opening at the front, the interior of the 40 casing having a non-light-reflecting surface, a parabolic reflector in the casing disposed below the window opening, a source of light adjustably mounted in the focus of the reflector, a flat surfaced mirror in the casing 45 above the parabolic reflector receiving the rays of light from the parabolic reflector and reflecting them through the window and means for adjusting the angularity of the 50 mirror from the outside of the casing.

4. In a vehicle lamp, the combination of a casing entirely inclosed except for a window opening at the front, the interior of the

casing having a non-light-reflecting surface, a parabolic reflector in the casing disposed 55 below the window opening, a source of light adjustably mounted in the focus of the reflector, a flat surface mirror in the casing above the parabolic reflector receiving the rays of light from the parabolic reflector, 60 and reflecting them through the window, means for adjusting the angularity of the mirror from the outside of the casing, said last-named means including a screw member and a traveling nut and a pivot for the 65 mirror with connections between the nut and mirror whereby on turning the screw the mirror is tilted.

5. In a vehicle lamp, the combination of a casing entirely inclosed except for a window opening at the front, the interior of the casing having a non-light-reflecting surface, a parabolic reflector in the casing disposed 75 below the window opening, a source of light adjustably mounted in the focus of the reflector, a flat surfaced mirror in the casing above the parabolic reflector receiving the rays of light from the parabolic reflector and reflecting them through the window, and means for moving the mirror horizontally or vertically to direct the reflected rays through the window, either up or down 80 or to the right or left.

6. In a headlight, the combination of a casing having a window opening at one side, a concealed source of light therein, means, including a parabolic reflector and mirror, by which the rays may be concentrated and reflected through the window, and means by which the direction of the 90 reflected rays through the window may be varied to right or left through the medium of the mirror in the casing.

7. In a headlight, the combination of a casing having a window opening at one side, 95 a concealed source of light therein, means, including a parabolic reflector and mirror, by which the rays may be concentrated and reflected through the window, and means by which the direction of the reflected rays 100 through the window may be varied to right or left, or vertically, through the medium of the mirror in the casing.
